(57) **CLAIM**

The ornamental design for an elf toddler doll as shown and described.

DESCRIPTION

FIG. 1 is a right side exploded view of an elf toddler doll; FIG. 2 is a front exploded view thereof;

FIG. 3 is a left side exploded view thereof;

FIG. 4 is a rear exploded view thereof;

FIG. 5 is a right side view thereof;

FIG. 6 is a front view thereof;

FIG. 7 is a left side view thereof;

FIG. 8 is a rear view thereof;

FIG. 9 is a front exploded perspective view thereof; and,

FIG. 10 is a front perspective view thereof.

The broken lines within FIGS. 4 and 8 depict portions of the elf toddler doll that form no part of the claimed design.

1 Claim, 10 Drawing Sheets
